UNITED STATES PATENT OFFICE.

FRANK E. LADD, OF SPRINGFIELD, MASSACHUSETTS.

DESIGN FOR A SPOON.

SPECIFICATION forming part of Design No. 28,091, dated December 28, 1897.

Application filed September 28, 1897. Serial No. 653,379. Term of patent 7 years.

To all whom it may concern:

Be it known that I, FRANK E. LADD, a citizen of the United States of America, residing in Springfield, in the county of Hampden and State of Massachusetts, have invented and produced a new and original Design for a Spoon, of which the following is a specification, reference being had to the accompanying drawing, forming a part thereof.

10 In the drawing I have illustrated my new design.

As shown in the drawing, the leading features of my design consist in the representation of a mountain, a park, and buildings.

15 The representation of the mountain, with a building and railway, is arranged upon the

handle and the remainder of the ornamentation is arranged in the bowl.

It is apparent that the design may be employed upon spoons of various sizes and that 20 the ornamentation shown upon the handle might also be employed on fork and other handles.

Having therefore described my invention, what I claim, and desire to secure by Letters 25 Patent, is—

The design for a spoon as herein shown and described.

FRANK E. LADD.
